US0D1088232S

(12) **United States Design Patent** (10) **Patent No.:** **US D1,088,232 S**
(45) **Date of Patent:** **** Aug. 12, 2025**

(54) **ELECTROMEDICAL DEVICE**

(71) Applicant: **Siemens Healthineers AG**, Forchheim (DE)

(72) Inventors: **Roman Achleitner**, Nuremberg (DE); **Stefanie Guegel-Wild**, Langensendelbach (DE); **Aurel Jensch**, Eggolsheim (DE); **Xiao Yan Du**, Shanghai (CN)

(73) Assignee: **Siemens Healthineers AG**, Erlangen (DE)

(**) Term: **15 Years**

(21) Appl. No.: **29/708,869**

(22) Filed: **Oct. 10, 2019**

(30) **Foreign Application Priority Data**

Apr. 12, 2019 (EM) 006377628

(57) **CLAIM**

The ornamental design for an electromedical device as shown and described.

DESCRIPTION

FIG. 1 is a front elevational view of an electromedical device showing our new design;

FIG. 2 is a back elevational view thereof;

FIG. 3 is a top plan view thereof;

FIG. 4 is a bottom view thereof;

FIG. 5 is a right side elevational view thereof;

FIG. 6 is a left side elevational view thereof; and,

FIG. 7 is a perspective view taken generally from the top, front, right-hand side thereof.

The broken lines shown in the drawings represent portions of the electromedical device that form no part of the claimed design.

1 Claim, 7 Drawing Sheets
